[57] CLAIM

The ornamental design for a headlight washer, as shown and described.

DESCRIPTION

FIG. 1 is a front elevation of a headlight washer showing my new design;

FIG. 2 is a rear elevation thereof;

FIG. 3 is a right side elevation thereof;

FIG. 4 is a left side elevation thereof;

FIG. 5 is a top plan view thereof; and,

FIG. 6 is a bottom plan view thereof.

The broken line showing of environmental structure in FIGS. 3 and 4 of the drawing is for illustrative purposes only and forms no part of the claimed design.
